HAIR CLIPPER

Matthew G. Andis, Racine, Wis., assignor to Andis
Clipper Co., Racine, Wis., a corporation of Wisconsin

Filed Feb. 1, 1962, Ser. No. 68,606

Term of patent 14 years

(Cl. D22—5)

FIG. 1 is a view in perspective of a hair clipper showing my new design.

FIG. 2 is a top plan view thereof.

FIG. 3 is a side elevational view.

FIG. 4 is a bottom plan view.

FIG. 5 is a rear elevational view.

My improved hair clipper design includes a casing which is narrower at its front end, adjacent the cutting head, than it is at its rear end. Its top, bottom and sides are nearly rectilinear in transverse section. Its top has substantially continuous convexity longitudinally, while its bottom surface is nearly flat in an intermediate area from which it curves upwardly in a short forward por-

tion adjacent the clipper head and from which there extends an upwardly inclined and relatively elongated rear bottom surface.

I claim:

The ornamental design for a hair clipper, substantially as shown and described.
